AMUSEMENT DEVICE

John Wunner, South Plainfield, N. J.

Application May 28, 1936, Serial No. 82,277

4 Claims. (Cl. 273—102)

This invention relates to amusement devices of the type presenting a plurality of targets at which missiles, such as baseballs, may be directed and which are adapted to so function in conjunction with suitable signals as to indicate the scoring of direct hits.

An important object of the invention is to provide an improved device of the character mentioned which is relatively simple in construction, inexpensive to manufacture and capable, by reason of the peculiar effects which are produced in response to direct hits, of gaining and maintaining interest on the part of those desiring to test their accuracy of aim or ability to score direct hits on the various targets.

Although the invention may assume many forms, it is herein illustrated as embodied in a device presenting a target figure shaped to simulate a face with eyes, nose and chin, with which are associated targets, which, when hit by a missile such as a baseball, are adapted to yield under impact and to then exercise such control over their respectively associated indicator means as to give the effect of a black eye in response to a direct hit on either of the eye-targets, the effect of a pair of black eyes in response to a direct hit on the nose-target and to present a flag and ring a bell in response to a direct hit on the chin-target.

Other objects and advantages of the invention will become apparent when taken in connection with the accompanying drawings in which—

Fig. 1 is a front view of a device embodying the invention; Fig. 2 is a plan view of the device; Fig. 3 is a vertical, sectional view taken substantially on line 3—3 of Fig. 1, and Fig. 4 is a fragmental, sectional view taken substantially on line 4—4 of Fig. 1.

Referring to the drawings, the numeral 5 indicates a base or support comprising a pair of transverse frame members 6, on which are supported a central frame member 7 and a pair of side frame members 8. To the front end of the base 5 there is connected a vertically disposed panel 10 which is securely anchored with respect to the base 5 by a pair of braces 11, connected at their upper ends to the rear of the panel and at their lower ends to the side frame members 8. Disposed at the rear of the panel 10 is a vertical frame member 12, which is connected to the central frame member 7 and securely anchored in a vertical position by a brace 14, the lower end of which is connected to the frame member 7.

To the front of the panel 10 there is connected a target figure, which is indicated generally by

the numeral 15, and is shaped to simulate a face having eyes, a nose and a chin, with which are respectively associated targets in the form of button-like elements 16, 17 and 18. These button-like elements are connected to the outer ends of a series of push-rods 20, 21, and 22 and are adapted, when moved under impact, to engage ring-like rubber cushioning elements 24, which are carried within cup-like recesses 25 formed in the eye areas, the nose area and the chin area of the face. Normally the push-rods 20, 21, and 22 are maintained in forwardly extended positions by compression springs 26, the rear ends of which engage the frame member 12 and the forward ends of which engage collar-like elements 27 secured to the respective push-rods at the rear of the front panel 10. From the foregoing it will become apparent that the collars 27 not only serve as abutments against which the springs 26 act, but also as means for limiting the push-rods in their return movements pursuant to their being moved against the action of the springs incident to the scoring of a direct hit on any one of the targets, namely, the button-like elements 16, 17, and 18.

The frame member 12 serves in conjunction with the front panel 10 and the target figure 15 as means for slidably supporting the push-rods 20, 21, and 22 and also as a support for various elements, entering into and forming parts of certain indicator means, hereinafter more particularly described, which are rendered operative in response to a direct hit on the respective targets 16—17—18. At the rear of the frame member 12 there is connected a bearing plate 28, having a pair of rearwardly extending marginal wings 29 to which are pivotally connected a pair of substantially U-shaped arms 30 and 31, to the free ends of which are suitably connected a pair of indicators in the form of disks 32 and 34 respectively. Pivotally connected to the wings 29 are a pair of arm-actuating fingers 35 and 36, on the outer ends of which the arms 30 and 31 normally rest, each of the fingers being formed near its pivot point with a heel-like extension 37. To the wings 29 are pivotally connected a pair of rocker arms 38, the lower ends of which are adapted to cooperate with the heel-like extension 37 and the upper ends of which are adapted to cooperate with the rear ends of each of the pair of push-rods 20. By reason of the relation between the push-rods 20, the rocker arms 38 and the U-shaped arms 30—31, it is apparent that a sudden rearward movement of one or the other of the push-rods 20 will cause its associated U-

shaped arm to move from its full line position shown in Fig. 3 to its dotted line position shown therein. Thus, it will be appreciated that if a direct hit is scored with sufficient force of impact 5 on the right eye target 16, the disk 32 will come to rest directly in front of the right eye; whereas as if a direct hit is scored on the left eye target 16, the disk 34 will assume a position directly in front of the left eye. If the target figure 15 is 10 viewed from a substantial distance in front thereof, the presence of either of the disks 32-34 at the front of the figure will give the illusionary effect of a black eye, since the disks are themselves black. In order to augment such illusionary effect, the U-shaped arms 30 are so colored 15 that they, when moved to their dotted line positions (see Fig. 1) blend with the background colors of the target figure 15.

In order that the U-shaped arms 30 and 31 20 may be simultaneously moved from their full line positions shown in Fig. 3 to their dotted line positions shown therein in response to a direct hit on the nose target 17, there is provided an elevating arm 40 which is pivotally connected to 25 the wings 29 at a point intermediate the same. The outer end of the elevating arm 40 is provided with a T-piece 41 which is of sufficient length to engage both of the arm-actuating fingers 35 and 36. The inner end of the elevating arm 40 is provided with a heel-like extension 30 42, adapted to cooperate with the lower end of a rock lever 44, which is pivotally connected to the wings 29 intermediate the same, the upper end of the rock lever being adapted to cooperate with 35 the rear end of the push-rod 21. In view of the relation existing between the push-rod 21, the rock lever 44, the elevating arm 40 and the pair of arm-actuating fingers 35 and 36, it will become apparent that, in response to a direct hit on the 40 nose-target 17, both of the U-shaped arms 30-31 will be moved simultaneously from their full line positions in Fig. 3 to their dotted line positions therein, thus producing the effect of a direct hit resulting in a pair of black eyes.

In order that the U-shaped arms 30 and 31 45 may be restored to their normal positions, each arm is equipped with a cord 45 or the like, which is anchored intermediate its ends to a spring-like finger 46 secured to the upper end of a spring 50 supporting post 47. Each of the cords 45 extends downwardly through a suitable guide 48 and forwardly through an opening 49 provided at the front of the device, it being observed that a sufficient amount of slack is allowed in the cord 55 intermediate the spring-like finger 46 and the point at which such cord is connected to its corresponding U-shaped arm 30-31, to permit that arm to move unobstructedly from its normal position to its dotted line position shown in 60 Fig. 3. From the foregoing it is obvious that the U-shaped arms 30-31, or either of them, may be conveniently returned to their normal positions from a remote location with reference to the device, as at the station from which the 65 baseballs or other objects are delivered or impelled toward the target figure 15.

As shown most clearly in Fig. 2, the brace 14 is provided intermediate its ends with a slot "S", adapted for the reception of a flagstaff socket 50, 70 which is pivotally connected to the brace as shown most clearly in Fig. 3 and is provided at one end with a weight 51, adapted to move the flagstaff socket from its full line position shown in Fig. 3 to its dotted line position shown therein. Carried by the socket 50 is a flagstaff 52 with

which is associated a flag 54, the flagstaff and flag being adapted to move from a substantially horizontal position generally at the rear of the device to a vertical position as indicated by dotted lines in Fig. 3. In order that the socket 50 and 5 its associated flagstaff 52 and flag 54 may be retained in normal positions subject to release in response to a direct hit on the chin-target 18, there is provided a latch 55 which is pivotally connected to the wings 29 at a point intermediate 10 the same. The latch 55 is normally maintained in its retaining position, shown in Fig. 3, by a compression spring 56, the opposite ends of which are confined within sockets 57 and 58 formed respectively in the latch and the frame member 12. 15 As shown most clearly in Fig. 3, the upper end of the latch 55 is disposed in a cooperative relation to the push-rod 22, so that movement of that rod in response to a direct hit on the chin-target 18 will cause the latch to move from its 20 position shown in Fig. 3 to a position of release, whereupon the flagstaff socket 50 is permitted to move under the action of the weight 51 in a counter-clockwise direction, as viewed in Fig. 3, thus allowing the flag 54 to be viewed from a 25 position generally in front of the device.

A direct hit on the chin-target 18 results, not only in presentation of the flag 54, but also in the giving of an audible signal, as through the medium of an electric bell generally indicated by 30 the numeral 60. The circuit closer for the bell 60 includes a pair of contact strips 61, carried by the brace 14 adjacent the slot "S" thereof and adapted to be electrically connected with each other by a contact element 62 (secured to the flagstaff socket 50) upon movement of that socket from its full line position in Fig. 3 to its dotted line position indicated therein. Conveniently located generally at the rear of the panel 10 is an electric battery "B", the cells 64 of which are 40 connected in series and the terminals 65 and 66 of which are connected, respectively, by conductors 67 and 68 to one of the bell terminals 70 and one of the contact strips 61, the other contact strip being connected by a conductor 71 to the 45 other bell terminal 72.

In order that the flagstaff socket 50, the flagstaff 52 and the flag 54 may be returned from their dotted line positions shown in Fig. 3 to their normal positions, the flagstaff 52 is equipped 50 with a cord 74, or the like, which passes downwardly through a suitable guide 75 and outwardly through an opening 76 provided at the front of the device, it being understood that the cord 74 55 may be of a length corresponding to the length of the cords 45 so as to enable all of the indicator units of the apparatus to be reset from a given location in front of and remote to the apparatus.

Although only one form of the invention is herein shown and described, it will be understood 60 that various modifications may be resorted to without departing from the spirit of the invention or the scope of the following claims.

What is claimed is:

1. An amusement device comprising a target 65 figure, a pair of movable targets associated with said figure and adapted to be moved under a force of impact delivered thereto, direct hit indicating means comprising a pair of indicator-carrying arms pivotally supported at the rear of said figure, a pair of arm-actuating fingers pivotally supported independently of each other and of said arms at the rear of said figure and adapted respectively to be moved in response to a force of impact delivered to said targets and to in turn 70 75 75

swing said indicator-carrying arms respectively from their normal positions of rest at the rear of said figure toward the front thereof, a third movable target associated with said figure and adapted to be moved under a force of impact delivered thereto and an elevating arm pivotally supported independently of said indicator-carrying arms and said fingers at the rear of said figure and adapted to be moved in response to a force of impact delivered to said third target and to in turn simultaneously swing said indicator-carrying arms from their normal positions of rest at the rear of said figure toward the front thereof.

2. An amusement device comprising a target figure, a pair of movable targets associated with said figure and adapted to be moved under a force of impact delivered thereto, direct hit indicating means comprising a pair of indicator-carrying arms pivotally supported at the rear of said figure, a pair of arm-actuating fingers pivotally supported independently of each other and of said arms at the rear of said figure and adapted respectively to be moved in response to a force of impact delivered to said targets and to in turn swing said indicator-carrying arms respectively from their normal positions of rest at the rear of said figure toward the front thereof, a third movable target associated with said figure and adapted to be moved under a force of impact delivered thereto, an elevating arm pivotally supported independently of said indicator-carrying arms and said fingers at the rear of said figure and adapted to be moved in response to a force of impact delivered to said third target and to in turn simultaneously swing said indicator-carrying arms from their normal positions of rest at the rear of said figure toward the front thereof and an indicator carried by each of said indicator-carrying arms and adapted to be moved generally forwardly with them from an obscure position at the rear of said figure toward the front thereof.

3. An amusement device comprising a target figure, a movable target exposed at the front of said figure and adapted to be moved under a force of impact delivered thereto, and direct hit

indicating means comprising a substantially U-shaped indicator-carrying arm pivotally supported at the rear of said figure with its leg portions normally extending upwardly, the length of the leg portions of said U-shaped indicator-carrying arm as well as the base portion thereof being such that said indicator-carrying arm when moved upwardly and forwardly about its point of pivotal support is adapted to straddle said figure, and an arm-actuating finger pivotally supported independently of said indicator-carrying arm at the rear of said figure and adapted to be moved in response to a force of impact delivered to said target and to in turn swing said indicator-carrying arm from a normal position of rest at the rear of said figure into a straddling relation to said figure.

4. An amusement device comprising a target figure, a movable target exposed at the front of said figure and adapted to be moved under a force of impact delivered thereto, and direct hit indicating means comprising a substantially U-shaped indicator-carrying arm pivotally supported at the rear of said figure with its leg portions normally extending upwardly, the length of the leg portions of said U-shaped indicator-carrying arm as well as the base portion thereof being such that said indicator-carrying arm when moved upwardly and forwardly about its point of pivotal support is adapted to straddle said figure, an arm-actuating finger pivotally supported independently of said indicator-carrying arm at the rear of said figure and adapted to be moved in response to a force of impact delivered to said target and to in turn swing said indicator-carrying arm from a normal position of rest at the rear of said figure into a straddling relation to said figure, and an indicator carried by one of the legs of said indicator-carrying arm and adapted to move therewith from an obscure position at the rear of said figure to a position in front of said target as said indicator-carrying arm assumes a straddling position with relation to said figure.

JOHN WUNNER. 45
